Primary Examiner — Darlington Ly(74) *Attorney, Agent, or Firm* — Christopher A. Proskey; BrownWinick Law Firm(57) **CLAIM**

The ornamental design for a track for use with a guided circular saw, as shown and described.

DESCRIPTION

FIG. 1 is a bottom perspective view of a guided track for circular saw showing my new design;

FIG. 2 is a top perspective view thereof;

FIG. 3 is a bottom plan view thereof;

FIG. 4 is a top plan view thereof;

FIG. 5 is a front elevation view thereof, to which the rear elevation view is a mirror image; and,

FIG. 6 is a right side elevation view thereof, to which the left side elevation view is a mirror image.

1 Claim, 6 Drawing Sheets(56)
